CLAIM

The ornamental design for tool for inserting and removing terminal lug cap, as shown and described.

DESCRIPTION

FIG. 1 is a perspective view of a tool for inserting and removing a terminal lug cap showing my design, the broken lines being shown therein for illustrative purposes only.

FIG. 2 is a front view of the tool.

FIG. 3 is a right side view of the tool.

FIG. 4 is a back view of the tool.

FIG. 5 is a left side view of the tool.

FIG. 1

FIG. 4

FIG. 3

FIG. 5

FIG. 2
